(57) **CLAIM**

The ornamental design for a pet car seat cover as shown and described.

DESCRIPTION

FIG. 1 is a perspective view of a pet car seat cover showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1;

FIG. 10 is an enlarged view of area 10 shown in FIG. 1;

FIG. 11 is an enlarged view of area 11 shown in FIG. 1;

FIG. 12 is an enlarged view of area 12 shown in FIG. 1;

FIG. 13 is an enlarged view of area 13 shown in FIG. 2;

FIG. 14 is an enlarged view of area 14 shown in FIG. 5; and,

FIG. 15 is a perspective view in which the pet car seat cover is in a condition of use.

The broken lines depict portions of the pet car seat cover that form no part of the claimed design. Additional dot dash lines depict area of enlargement indicators and form no part of the claimed design.
